his Attorneys.

UNITED STATES PATENT OFFICE.

HENRY O'B. HARDING, OF MINNEAPOLIS, MINNESOTA, ASSIGNOR TO WASHBURN
CROSBY COMPANY, OF MINNEAPOLIS, MINNESOTA, A CORPORATION.

CONVEYER.

1,352,263.

Specification of Letters Patent.

Patented Sept. 7, 1920.

Application filed December 26, 1918. Serial No. 268,373.

To all whom it may concern:

Be it known that I, HENRY O'B. HARDING, a citizen of the United States, residing at Minneapolis, in the county of Hennepin and State of Minnesota, have invented certain new and useful Improvements in Conveyers, of which the following is a specification.

My invention relates to conveyers and particularly conveyers intended for use in mills for conveying filled sacks to a sewing machine or other device for closing the tops of the sacks. An object of my invention is to provide a portable conveyer which may be readily moved into any desired position. Another object is to provide a conveyer which will operate with a steady uniform movement without tendency to upset filled sacks placed thereon.

20 The full objects and advantages of my invention will appear in connection with the detailed description thereof and the novel features embodied in my inventive idea are particularly pointed out in the 25 claims. In the accompanying drawings which illustrate the application of my invention in one form,

Figure 1 is a view in side elevation. Fig. 2 is a top plan view. Fig. 3 is an enlarged 30 view in longitudinal section on line 3—3 of Fig. 2. Fig. 4 is an enlarged view in cross section on the line 4—4 of Fig. 2 looking in the direction of the arrow. Fig. 5 is a side view showing the manner in which 35 my conveyer may be used for conveying sacks.

As shown in the drawings, two transverse base members 10 are mounted on small wheels 12. Extending upwardly from the 40 base members are pairs of adjustable standards 14, to the upper ends of which is secured the frame of the conveyer. The frame comprises two longitudinal angle bars 16 secured to the standards and a series of 45 braces to be referred to later. Secured between the angle bars 16 is a longitudinal supporting member or table 18 which serves to support the upper stretch of a flexible endless belt 20 passing over a driving roller 50 22 at one end of the frame and a take-up roller 24 mounted in a support adjustable by a screw bolt 28 at the other end of the frame. The lower stretch of the belt is held up to the table by rollers 29 supported 55 by the frame. A shelf 30 attached to some

of the standards 14 is adapted to support an electric motor 32 operated by a current supplied by wires 34 having a plug 36 at their outer ends for insertion in any suitable plug socket. The motor shaft is geared 60 to a shaft 38 which by means of the gearing contained in a gear case 40 turns the roller 22 to drive the belt. The longitudinal bars of the frame are held together and braced by end plates 42 and strips 44, the 65 upper ends of which are secured to the angle bars, said plates and strips being bent inwardly under the conveyer and having their lower ends secured to a longitudinal angle bar 46 extending in a line beneath 70 the median line of the table. Additional strips 48 located adjacent the standards 14 have their upper ends secured to the angle bars 16 and their lower ends secured to the standards. The strips 44 and 48 are inclined with relation to the direction of the length of the frame whereby the latter is very effectively braced. Secured lengthwise 75 to the vertical sides of the angle bars 16 are strips 50 the upper edges of which are 80 turned over the top edges of the angle bars and brought down close to the upper stretch of the belt 20 to form a close joint and prevent dirt and dust obtaining an entrance below the upper stretch of the belt. Fig. 5 85 shows the conveyer in use to carry sacks of flour underneath a sewing machine 52 which sews up the top of the sacks, the closed sacks being delivered by the conveyer to a cross belt 53 which takes them to an 90 elevating device 54.

The operation and advantages of my invention will be obvious from the foregoing description. On account of the electric motor being mounted upon the conveyer the 95 latter may be readily rolled from place to place as desired. A rigid support upon which the endless belt is adapted to move in a constant plane is provided and hence there is no jerking or flopping of the belt 100 which would tend to upset filled sacks placed thereon for conveying to a sewing machine or other device for closing the tops of the sacks.

I claim:

1. A conveyer comprising wheeled standards, a pair of longitudinally extending bars secured to said standards, a table secured to said bars, inclined bracing strips secured at their upper ends to said bars, the 110

- lower ends of some of said strips being secured to said standards and the lower ends of the rest of the strips extending into a line beneath the median line of said table, an angle bar secured to said last mentioned strip-ends, an endless belt extending longitudinally around said table with its upper stretch in contact therewith, and means for driving said belt. 20
- 5 2. A conveyer comprising wheeled standards, a pair of longitudinally extending angle bars secured to said standards, a table secured to said angle bars, plates secured to the ends of said angle bars, inclined bracing strips secured at their upper ends to said angle bars, the lower ends of some of said strips being secured to said standards and the lower ends of the rest of the strips and also the lower ends of said plates ex- 25
- 10 15

tending into a line beneath the median line 20 of the table, an angle bar secured to said last mentioned strip-and-plate-ends, an endless belt extending longitudinally around said table with its upper stretch in contact therewith, and means for driving said belt. 25

3. A conveyer comprising wheeled standards, a pair of longitudinally extending bars secured to said standards, a table secured to said bars, a traveling belt in contact with said table and extending between 30 said bars and strips secured to said bars, the upper edges of said strips being turned over the top edges of said bars to form a close joint with said belt.

In testimony whereof I hereunto affix my 35 signature.

HENRY O'B. HARDING.
